UNITED STATES PATENT OFFICE.

WALTER L. DOUGLASS, OF BUFFALO, NEW YORK.

DESIGN FOR A FLOWER-POT HOLDER.

SPECIFICATION forming part of Design No. 26,106, dated September 29, 1896.

Application filed August 10, 1896. Serial No. 602,365. Term of patent 14 years.

To all whom it may concern:

Be it known that I, WALTER L. DOUGLASS, a citizen of the United States, residing at Buffalo, in the county of Erie and State of New York, have invented and produced a new and original Design for Flower-Pot Holders, of which the following is a specification, reference being had to the accompanying drawing, showing a part thereof.

10 This invention relates to a design for a holder or receptacle adapted to receive a flower-pot.

15 The accompanying drawing, which forms part hereof, is a perspective view of a flower-pot holder embodying the design.

20 The leading feature of my design consists of a horizontal bottom ring, a tapering pin extending downward from said bottom ring, a top ring arranged above said bottom ring, and upright bars extending from the top ring to the bottom ring.

25 Referring to the accompanying drawing, A

is the horizontal bottom ring, and b are radial bars meeting at the middle of the ring and extending outwardly to the same.

25

C is the tapering pin or projection, extending downward from the junction of the radial bars b.

D is the top ring, arranged above the bottom ring, and E are the upright bars, which extend from the top ring to the bottom ring. The top ring is somewhat larger in diameter than the bottom ring, giving the holder a flaring or tapering appearance, as shown.

35

What I claim is—

The design for a flower-pot holder, substantially as herein shown and described.

Witness my hand this 4th day of August, 1896.

30
WALTER L. DOUGLASS.
